UNITED STATES PATENT OFFICE.

JASPER F. CULLIN, OF DETROIT, MICHIGAN, ASSIGNOR TO WILLIAM J. HARTWIG, OF DETROIT, MICHIGAN.

COIL-WINDER.

1,397,316.

Specification of Letters Patent. Patented Nov. 15, 1921.

Application filed November 12, 1920. Serial No. 423,675.

To all whom it may concern:

Be it known that I, JASPER F. CULLIN, a citizen of the United States, and residing at Detroit, in the county of Wayne and State 5 of Michigan, have invented a new and Improved Coil-Winder, of which the following is a specification.

This invention relates to means for winding wire coils, particularly for electric 10 motors and generators, and is of the same general type as that shown in my prior application Serial Number 407,708, filed September 2, 1920, and its object is to provide means for simultaneously shearing free the two 15 ends of the just previously wound coil and securing the end of the supply wire to a part of the winder for the winding of the next coil.

This invention consists in combination 20 with a winder for coils comprising two members, one having a rectangular hub with inclined edges and the other member being adapted to fit against and be secured to the first to cause the strands at the ends of the 25 coil to keep their proper positions, of a shaft on which the winder is mounted, a plate on the shaft adjacent the winder and having a plurality of fingers, and shear members mounted on the plate and adapted 30 to coact with the fingers to shear the ends of the coil.

It further consists in so positioning the shear members and the fingers that the shear member which cuts the coil from the supply 35 wire also bends the end of the supply wire around one of the fingers so that the wire may be drawn from the supply when the winder is rotated.

It also consists in so positioning another 40 shear member that when the coil is completed this shear member will cut off the bent over end of the wire.

It also consists in the details of construction illustrated in the accompanying drawings 45 and particularly pointed out in the claims.

In the accompanying drawings, Figure 1 is an elevation of this improved coil winder. Fig. 2 is a similar plan with the shearing means at the ends of the cutting strokes. Fig. 3 is a section on the line 3—3 of Fig. 1. Fig. 4 is an end view taken from the left in Fig. 1. Fig. 5 is a plan of the winding head and shear. Fig. 6 is a section on the 50 line 6—6 of Fig. 3.

Similar reference characters refer to like parts throughout the several views.

Any desired means may be employed to support the spindle 1 and to rotate it the desired number of times to cause it to wind 60 a coil, as explained in my former application. The outer end 2 of this spindle is preferably enlarged and on it is slidable a sleeve 3 having a groove 4 and a conical outer end 5. A lever 6 pivoted at 7 has a pair of arms 65 8 provided with pins 9 that extend into the groove 4 and by means of which the sleeve may be moved back and forth along the shaft.

A collar 10 and plate 11 are mounted on 70 the outer end of the spindle and from the main portion of the plate extend the three fingers 13, 14 and 15 which carry the pivot 16 on which the shear levers A and B are mounted. The fingers 14 and 15 are similar, 75 being provided with inclined faces 17 leading to the shear edges 18 on these fingers. The upper end 21 of the upper arm 22 of the lever A has a notch 23 to receive the supply wire 20 from which the coil is wound, 80 and when this lever is swung from the position shown in Fig. 1 to that shown in Fig. 2, shears this wire in coöperation with the edge 18 of the finger 14. The forwardly extending upper end 24 of the upper arm 25 85 of the shear lever B coöperates with the shearing edge 19 of the finger 15 to shear another portion of the wire at the same time as the shear lever A is operating. The rear or lower ends 26 and 27 of these levers are 90 connected by the block 28 and the bolt 29. The end of the arm 27 is rounded to engage the conical end 5 of the sleeve 3. An outward movement of this sleeve will swing the cutting edge of these levers across the shear 95 edges of the fingers 14 and 15.

Mounted on the outer end of the spindle is a winder plate 30 and a central pin 31 onto which a follower plate 32 may be locked by means of a latch 33 after being positioned by the dowel-pins 34. The pin 31 has a groove 35 to receive the latch. The follower plate has a rectangular hub 37 and oppositely extending radial ribs 38, the edges of the hub being beveled as shown in 100 Figs. 1 and 2.

A finished coil 39 is shown on the winder in Fig. 4 and a clip 40 is shown holding the wraps together so that they will not uncoil when released. The lever 6 is then swung 110

to the position shown in Fig. 2, which causes the upper end 21 of the shear member A to sever the end 42 of finished coil, which end immediately falls, and the upper end 24 of the shear member B to sever the supply wire 20 at 43, which permits the end 41 to spring out as indicated in Fig. 4. It will be noticed in Fig. 4 that there is a space between the side of the end 24 of the lever B and upper end of the adjacent finger 14.

14. When this end of the lever is swung forward, it bends the end 44 (Fig. 5) of the supply wire into this space and around the finger 14.

15. The latch 33 is then swung (to the right in Fig. 4) to release the pin 31, and the follower plate and the finished coil thereon is lifted off the pin 31 to permit the finished coil to fall. The follower is immediately replaced and locked and the shaft 1 is started rotating. The supply wire 20 swings down (relatively) along the front edge of the finger 13 and is carried by the inclined edge 45 thereof to the space between the plates 30 and 32 of the winder 25 wherein the wire is wound the desired number of wraps, passing in front of the fingers 14 and 15 while being thus wound. Just before the winder stops, the operator guides 30 the wire into the notches in the ends of the fingers into the path of the shear member 24, as shown in Fig. 4.

The shear members are returned by the coil spring 46 which extends around the 35 collar 10 and has its ends hooked around the parts 26 and 27 of the shear members, being held in position by the pin 47. The operator therefore has only to swing the lever 6, remove the plate 32 and replace 40 it, start the shaft rotating, and at the end of the winding guide the supply wire into the notches in the ends of the fingers 14 and 15.

The details and proportions of the several 45 parts of this winding machine may all be changed by those skilled in the art without departing from the spirit of my invention as set forth in the following claims.

I claim:—

50 1. In a winding machine for coils, the combination of a shaft and two winder plates mounted on the end thereof, and formed with central contacting portions on which the coils may be wound, and a shearing device mounted on said shaft and rotatable with said plates and having a plurality of cutting members to sever the ends of the finished coils.

55 2. In a winding machine for coils, the

combination of a shaft and two winder plates mounted on the end thereof, and formed with central contacting portions on which the coils may be wound, and a shearing device mounted on said shaft and rotatable with said plates and having a plurality of cutting members to sever the ends of the finished coils and to bend the end of the supply wire around one part of the shearing device.

3. In a winding machine for coils, the combination of a shaft and a winding device at the end of said shaft, a plate mounted on the shaft adjacent the winding device and a plurality of fingers extending therefrom and having notches in their ends, and shear levers mounted on the plate and adapted to shear the ends of finished coils.

4. In a winding machine for coils, the combination of a shaft and a winding device at the end of the shaft, a plate mounted on the shaft adjacent the winding device and a plurality of fingers extending therefrom, a shear lever mounted on the plate and adapted to shear the supply wire and bend its end around one of the fingers, and a second shear lever mounted on said plate and adapted to shear such bent over end from the finished coil.

5. In a winding machine for coils, the combination of a shaft and a winding device at the end of the shaft, a plate mounted on the shaft adjacent the winding device and a plurality of fingers extending therefrom, a shear lever mounted on the plate and adapted to shear the supply wire and bend its end around one of the fingers, a second shear lever mounted on said plate and adapted to shear such bent over end from the finished coil, said shear levers having arms extending along the shaft, means connecting said arms, and a sleeve slidable along the shaft and having a conical end adapted to engage the ends of said arms to swing the shear levers through their cutting strokes.

6. In a winding machine for coils, the combination of a shaft and a winding device at the end of said shaft, a plate mounted on the shaft adjacent the winding device and a plurality of fingers extending therefrom and having notches in their ends, shear levers mounted on the plate and adapted to shear the ends of finished coils, and a sleeve manually slidable along the shaft to engage said levers to cause said shearing operation.

JASPER F. CULLIN.
